UNITED STATES PATENT OFFICE.

LOUIS DUENNISCH, OF SANDUSKY, OHIO.

FLUE-CLEANER.

SPECIFICATION forming part of Letters Patent No. 388,848, dated September 4, 1888.

Application filed June 8, 1888. Serial No. 276,449. (No model.)

To all whom it may concern:

Be it known that I, LOUIS DUENNISCH, a citizen of the United States, residing at Sandusky, in the county of Erie and State of Ohio, have invented certain new and useful Improvements in Flue Cleaners, of which the following is a specification, reference being had therein to the accompanying drawings.

This invention relates to certain new and useful improvements in flue-cleaners; and the invention belongs to that class of devices wherein the cleaning of the tubes is performed by the action of steam.

My invention is designed to form an improvement on the device patented to me December 1, 1885, No. 331,691.

The object of my improvement is to render the device as shown in this previous patent applicable to any contingencies for which the prior one is not adapted; and my invention consists, first, in the peculiar construction of a composite rigid and flexible handle, whereby the head of the flue-cleaner may be readily inserted and pushed through the tube without requiring the extended floor-space which an all-rigid handle would require; further, in the peculiar construction of the head of the flue-cleaner, by means of which the same is made reversible, and also adapted to be used as a steam-blower for various purposes in which such an application may be of benefit in the general cleaning of boilers and flues of all kinds where the cleaning can be accomplished by means of steam.

In the drawings which accompany this specification, Figure 1 is a section through a boiler-flue with the head of my cleaner inserted therein, as in the act of cleaning. Fig. 2 is a perspective view showing the device complete and illustrating the manner of using it.

A is a hollow conical head, diamond-shaped in cross-section, and provided with the corresponding screw-threaded apertures B at both ends in the axial line of the head. Into one of these apertures is secured the hollow tube C, which forms the rigid part of the handle, while the other end is closed by the screw-block D, removably secured therein and preferably forming a point for the head. The largest diameter of this head is slightly smaller than the inner diameter of the boiler-flues on

which the device is intended to be used, so as to permit of its ready insertion and passage through the flue from end to end, even if the flues are covered with soot. Close to the largest diameter of the head, but in a plane parallel thereto and upon a smaller diameter, the head is provided with a series of circumferential oblique apertures or perforations, E, for the purpose of permitting the steam to issue from the head in oblique jets against the inner wall of the boiler-flue when the device is in operation, in order to produce the greatest mechanical effect of the steam upon the boiler-scale.

The tube C, which forms the rigid part of the handle, is made a few feet in length, (more or less,) and to its rear end the flexible part F of the handle is secured by means of a suitable coupling, G. This flexible handle is made of steam-hose, preferably wrapped with marline, and painted with a heavy coat of fire-proof paint to protect it from the wear and heat while in the flue. To the rear end of this flexible hose another suitable coupling, H, is secured—preferably a union-coupling—for the purpose of readily securing it to a convenient steam-connection with the boiler.

To protect the operator from burning his hands upon the handle C when operating it, I preferably provide it with the sliding handle I.

In practice, live steam from the boiler being admitted into the head by opening the valve J, the operator inserts the head of the device into the flue and pushes it gradually into the flue. By having a mark on the hose he is notified that the head has reached the rear end of the flue, when he withdraws it and passes it into another flue. With the handle thus constructed, part rigid and part flexible, the operator can clean one flue after another from the front of the boiler, requiring but little floor-space to move around, while at the same time his work is lightened, and the device may be conveniently stored away when not in use. By unscrewing the plug D and reversing the head on the tube the apertures are pointed toward the front, and the action of the steam when in operation will cause the soot and scales to be thrown toward the operator.

The object of making the head reversible is to enable the inexperienced operator to make

suitable tests to inform himself of the necessary pressure of steam to thoroughly clean the flues, as he can watch the result closely by using the head reversed, as in such position 5 the remaining soot and scales will be thrown forward toward the operator. After the proper experience has been acquired as to the pressure needed to clean the flues, the reversing of the head can be dispensed with.

10 What I claim as my invention is—

In a steam flue-cleaner, the hollow head, diamond-shaped in cross-section, correspondingly apertured at both ends in the axial line

of the head, the handle secured in the aperture at one end and the block removably secured in the other end, and the oblique steam-apertures in said head, substantially as and for the purpose described.

In testimony whereof I affix my signature, in presence of two witnesses, this 23d day of May, 1888.

LOUIS DUENNISCH.
